DESIGN FOR A TOY RATTLER

George W. Delano, Detroit, Mich.

Application March 26, 1945, Serial No. 118,696

Term of patent 7 years

(Cl. D34—15)

To all whom it may concern:

Be it known that I, George W. Delano, a citizen of the United States, residing at Detroit, in the county of Wayne and State of Michigan, have invented a new, original, and ornamental Design for a Toy Rattler, of which the following is a specification, reference being had to the accompanying drawing, forming part thereof.

Fig. 1 is a plan view of a toy rattler, showing my new design;

Fig. 2 is an end view of Fig. 1, and
Fig. 3 is a sectional view taken on line 3—3 of Fig. 1.

I claim:

The ornamental design for a toy rattler, as shown.

GEORGE W. DELANO.
